UNITED STATES PATENT OFFICE.

JOSEPH KÁLNA, OF BENNING, PENNSYLVANIA.

DESIGN FOR A CHRISTMAS-TREE HOLDER.

45,193.

Specification for Design.

Patented Feb. 3, 1914.

Application filed November 12, 1913. Serial No. 800,681. Term of patent 7 years.

To all whom it may concern:

Be it known that I, JOSEPH KÁLNA, a subject of the Emperor of Austria-Hungary, residing at Benning, in the county of Fayette and State of Pennsylvania, have invented a new, original, and ornamental Design for Christmas-Tree Holders, of which the following is a specification, reference being had to the accompanying drawing, forming part thereof.

The figure is a perspective view of a Christmas tree holder, showing new design.

I claim:

The ornamental design for a Christmas tree holder, as shown.

JOSEPH KÁLNA.

Witnesses:

ALLEN GALLEY,
STEVEN KOLESAR.
